UNITED STATES PATENT OFFICE.

ALFRED L. SOHM, OF CHICAGO, ILLINOIS, ASSIGNOR TO SOHM ELECTRIC SIGNAL & RECORDING COMPANY, OF CHICAGO, ILLINOIS, A CORPORATION OF ARIZONA.

ELECTRICAL RECORDING APPARATUS.

1,141,216.

Specification of Letters Patent. Patented June 1, 1915.

Application filed October 5, 1912. Serial No. 724,024.

To all whom it may concern:

Be it known that I, ALFRED L. SOHM, a citizen of the United States, residing at Chicago, in the county of Cook and State of Illinois, have invented a certain new and useful Improvement in Electrical Recording Apparatus, of which the following is a full, clear, concise and exact description, reference being had to the accompanying drawings, forming a part of this specification.

My invention relates to the art of automatic recording and contemplates an improved system and apparatus for making a record of periods of elapsed time.

More specifically, my present invention has to do with an electrically operated printing machine wherein certain selections, in the way of identifying numbers or letters, may be made.

It will appear to those skilled in the art that there may be other uses for my invention, but I contemplate its use particularly in keeping a record of an employee's time in an industrial establishment.

In order to facilitate the description of my invention, I explain it as part of a recording system wherein a number of employees are assigned, respectively, to an equal number of keys which they are supposed to actuate at the beginning and end of each period of working time. The results are printed on a strip of paper and it will be seen that it is necessary to distinguish one workman from another and I do this by means of a shifting type bar which, automatically, is brought into proper position by the manipulation of the proper key in order that the corresponding workman's number or letter may be registered with the other data printed at the same time. This shifting type bar is controlled by a number of electromagnets, two for moving the bar in both directions and two for determining the limits of certain movements of the bar.

In this way, certain combinations are produced in the electrical circuit arrangement in order that the bar may be made to occupy any one of a number of definite positions. I embody the peculiar arrangement which I have just described broadly in a printing machine which involves other printing

wheels, ribbon mechanism, and paper advancing mechanism, and I regard the entire combination as one of rare utility in the peculiar results which the association produces. I have, therefore, drawn claims, not only to the abstract type bar mechanism, but also to the mechanism in combination with the other parts.

My invention will be clearly understood by referring to the accompanying drawings, in which—

Figure 1 is an elevational view embodying the structural features of my invention; Fig. 2 is a cross-sectional view taken on lines 2—2 of Fig. 1; Fig. 3 is a top view of the structure shown in Fig. 1; Fig. 4 is a view taken on lines 4—4 of Fig. 1 showing the mechanism from the top after the printing mechanism has been removed; Fig. 5 is a sectional view taken on lines 5—5 of Fig. 3 showing the disk which engages the paper upon which the printing is done; Fig. 6 is a side view of the mechanism shown in Fig. 5; Fig. 7 is a top view of the electromagnets and the shifting type bar; Fig. 8 is a view similar to Fig. 7 except that the shifting bar is shown in another position; Fig. 9 is an elevational view of the mechanism shown in Figs. 7 and 8 showing the controlling magnets with the shifting bar. This view also shows part of the "In and out" mechanism; Fig. 10 is a cross-sectional view taken on lines 10—10 of Fig. 4; Fig. 11 is a cross-sectional view taken on lines 11—11 of Fig. 10; and Fig. 12 is a diagram illustrating the circuit arrangement employed in conjunction with the apparatus illustrated in the foregoing figures. Fig. 13 is a view of a part of the record strip, with a record printed thereon.

At the outset I shall refer to the structural embodiment of my invention. I have shown a foundation plate 13 which is suitably mounted in a supporting base 14. This plate 13 has extending upwardly therefrom a plurality of posts 15 which support a top plate 16. At one end of this plate, as shown in Figs. 1 and 3, there is mounted a pair of brackets 17, 17 which are connected by means of a yoke 18 which, in turn, supports two electromagnets 19, 19, having their cores

connected at the top by means of a yoke 20. A screw 21 passes between the electromagnets 19 and serves to fasten together the yokes 18 and 20. Each of the brackets 17 has a pivot 22 which support the arms 23, 23, these arms having attached thereto an armature 24 which is adapted to be attracted by the cores of the electromagnets 19, 19. The arms 23 are connected by a connecting rod 25 and have pivoted thereto at 26 two dogs 27 which are weighted at 28. These dogs are adapted to engage with ratchets 29 mounted on a pivot rod 30, which is supported in plates 31, 31 extending upwardly from the top plate 16. The pivot rod 30 is enlarged between the plates 31 as shown and supports two disks 32, 32 which have prongs or points 33, 33 along the periphery thereof. These points are adapted to engage the paper 34 which, as shown in Fig. 5, passes between the disk 32 and two smaller disks 35, these points being arranged so that they pass through the paper and engage the smaller disks 35 as shown. This arrangement provides a proper advancement of the paper upon the deenergization of the electromagnets. These disks 35, 35 are mounted upon a shaft 36 journaled in the extensions 37 extending from the side plates 31. This is shown particularly in Fig. 5. The arms 23 are provided at one extreme end with pivot pins 38 which engage with a reciprocating member 39 (sufficient play between the parts being provided) which is widened at 40 as shown in Fig. 2 and which has secured in a groove 41 a platen 42, the purpose of which will be described later. The member 39 has at its upper portion an elongated slot 43 through which a constricted portion of the stud 44 passes. This stud extends from a plate 45 at the front of the machine which is secured to the top plate 16 by means of screws 46. This plate 45 is provided at each side with spools 47 and 48 which are mounted upon pivot rods or screws 49 and 50, respectively, which, in turn, are fastened in the front plate 45. Each of these spools has attached thereto a ratchet, 51 or 52, which is adapted to be engaged by a pawl member 53 which is pivoted at 54 to the member 39. The member 53 is pointed at the lower end and engages a spring 55 which is mounted upon the member 39 and is provided with looped ends 56, 56 which engage around pins 57, 57.

The upper portion of the member 53 is bifurcated as shown and has at each side thereof prongs or points 58 which are adapted to engage with the ratchets 51 or 52 as may be desired. Pivoted upon the stud 44 and held thereon by means of a screw 59 is a lever 60 which has secured thereto a pin 61 which engages with the bifurcated end of the member 53 as shown. This lever 60 is in the nature of a retaining pawl for

either of the ratchets with which it may be placed into engagement as desired and to this end it is provided with an engaging portion 62 extending at right angles with the body of the pawl 60. The arrangement is such that after the member 53 has been thrown into either one of its positions, it will have a tendency to keep the pawl 60 in engagement with either one of the ratchets by means of the engagement of the limbs 63, 63 with the pin 61. In other words, the arrangement provides that the frame 39 may be moved downward when the electromagnets 19, 19 are energized, and during this movement the retaining pawl 60 is maintained in engagement with the ratchet 51, in this particular instance, and when the frame 39 is moved upward, under the action of the spring 64, the ratchet 51 and the associated spool will be advanced a predetermined distance. The spring 64 is secured at the top to a pin 65 extending from the front plate 45 and is secured to a pin 66 fastened to the frame 39 and extending through an elongated slot 67 in the front plate 45, this particular arrangement being shown in Figs. 1 and 2.

The spools 47 and 48 are protected by means of housings 68 and 69 which, as shown, are held in place by means of screws 49 and 50. These screws are threaded into the front plate 45 and extend backward so as to be engaged by thumb nuts 71, 71'. The housings 68 and 69 are cut away as shown at 70 and 71 so as to provide for the proper operation of the pawl 60 with each of the ratchets 51 and 52. The ribbon 72 which is fastened to each one of the spools is adapted to pass around rollers 73, 73 at each side of the frame, this ribbon, as shown, passing underneath the sheet of paper 34 and at the same time passing directly above the slot 74 in the plate 16. Suitable slots 75 are provided in the side plates 31, 31 through which the ribbon passes. When the ribbon has unwound from one spool the member 53 and pawl 60 may be manually thrown into engagement with the ratchet of this empty spool, thus reversing the direction of travel of the ribbon.

Proceeding now to a description of the mechanism for disposing the number of an employee in the path of the platen as it comes down, there is suitable mechanism in the form of a bar 76 which is provided with numerals 77 which are in the form of type, that is to say, they are raised from the surface of the bar so that the printing can be properly done. As shown in this instance, there are six numerals and a "W" at the center. This "W" may be used as the indication of a watchman who may be employed about the premises of the establishment during the evening or during the night time. The bar 76 is adapted to be recipro-

cated and to this end it is provided with teeth 78, which are engaged by a toothed-member 79 pivoted at 80 and provided at its lower end with a tapered armature 81 disposed in proximity to the cores of the electromagnets 82 and 83 which are suitably secured below the plate 13. (See Figs. 1 and 10). The bar 76 is provided with bosses or lugs of which there are three in this instance, one large central boss 84 and a smaller boss 85 at the right thereof, and a boss 86 at the left of the boss 84. The bosses 84 and 85 are adapted to be engaged by the armature 87 pivoted at 88 to a post 89, which has secured thereto a spring 90 which engages with one end of the armature 87 in order to maintain it in the "up" position. This particular arrangement is shown in Fig. 9, where the spring 90 engages an extension 91 on the armature and thereby keeps this extension in engagement with the post and consequently maintains the armature up above the path of the bosses 84 and 85 during the reciprocation of the bar 76. The armature 92 is arranged to be engaged by the bosses 84 and 86, as the case may be, when the electromagnet 93 is energized. This armature is mounted in the same manner as described in connection with the armature 87 and further description is deemed unnecessary. The armature 87 is brought into its down or attracted position by means of the electromagnet 94. Each magnet has two coils. The bar 76 is provided at each end with grooves 95 and 96 which are arranged to be engaged by pins 97 and 98 secured in the supporting posts 99 and 100 at each end of the rod 76. This arrangement is shown in Figs. 1, 4 and 9 particularly.

The circuit arrangement for controlling the electromagnets will be described later and we shall now describe the means by which the different numbers are placed into line with the platen 42 so that the printing of the proper number will be shown. Take for example, where an employee whose number is 6 enters the establishment. The circuit connections are such that the electromagnet 83 is energized and the armature 81 is pulled toward the left. This causes the member 79 to advance the rod 76 toward the right until the pin 101 strikes the supporting post 99, as shown in Fig. 7. If Number 1 had entered the establishment, then the pin 102 extending downwardly from the rod 76 would have engaged the supporting post 100 and thus limited the movement toward the left of the rod 76, whereby the numeral 1 would be brought into printing line with the platen 42, the magnet 82 being energized in this case. In order to maintain the bar 76 in its normal position as shown in Fig. 4, I have arranged a bracket 103 as shown in Fig. 10, which bracket has mounted thereon two springs 104 which project downwardly through a slot in the plate 13 and engage on each side of the pin 105 extending sidewise from the armature 81. These springs co-act so as to return the armature 81 to its normal position after either one of the electromagnets 82 or 83 has been energized. As shown in Fig. 8, the position of the parts is such that the numeral 5 is brought into the printing line and the armature 92 is shown as engaging with the boss 86. In other words, this armature has limited the movement of the bar 76 after the electromagnet 83 has been energized. This is referred to later. At this point, it might be well to describe the mechanism which indicates whether an employee is passing in or out of the establishment and to this end there is pivoted to the post 99 a lever 107 which is bifurcated at both ends. This lever engages at its end with an extension 108 from a reciprocating member 109 which is provided with the indications "In" and "Out" in relief letters. The lever 107 engages at its lower end with a member 110 which is pivoted at 111 and which has secured thereto an armature 112 which is adapted to be attracted by either one of the electromagnets 113 and 114 which are suitably secured to the plate 13. As shown in the drawings, the word "Out" is in line with the platen and when the platen is brought downward, this word will be printed upon the paper. In order to maintain the armature 112 in either one of its positions there is arranged a spring 115 which engages the lever 107 so as to cause a movement to either one of the extreme positions. In other words, an intermediate position is not desired since in this position no indication would appear as to whether the employee was passing out or into the establishment. This spring, it will be stated, is pointed at its center, like the spring 55, so as to throw the lever 107 into either one of its extreme positions, as determined by the energization of either one of the electromagnets 113 or 114.

Referring now to the mechanism which indicates the month, the day of the month, and the hour and the minute of the day, and also the year, there is disposed a rod 116 supported in the post 99 and in one of the posts 15. This rod supports a type wheel 117 indicating a plurality of years and a type wheel 118 indicating the months. The type wheels 119 indicate the day of the month and the type wheels 120 indicate the hour of the day or night. These type wheels 117 are provided with ratchets 121, all of which, except the one associated with the year wheel, are adapted to be engaged by suitable advancing pawls 122, which are secured upon the yoke 123 that is mounted upon the rod 116. A plurality of pawls 124 are mounted upon a rod 125 and are em-

ployed to engage the ratchets to prevent back rotation of the type wheels. These pawls are kept in engagement with the ratchets by means of springs 126 which are secured to a rod 127 extending between two side members 128, 128. This particular mechanism constituting the type wheel movement forms no part of my present invention and it is deemed sufficient to refer to it broadly and it is deemed sufficient to state that the minute type wheels are advanced by the advancing pawls every minute in accordance with the energization of two electromagnets 129 and 130 which support a yoke 131 to which is pivoted an armature 132 which has pivoted thereto at 133 a downwardly extending member 134 which is screw-threaded at its lower end and projects through an opening in the plate 13. The threaded portion is engaged by a thumb nut 135 which may be securely mounted by means of a screw.

The member 134 has a pin 136 extending therefrom which engages in an elongated slot 137 in a rod 138 which is pivoted at 139. This rod passes through an opening 140 in the plate 13 and extends downward and is hinged to a member 141 which passes upwardly through an opening in the plate 13 and is pivoted at 142 to a link 143 which, in turn, is pivoted at 144 to an extension 145 from the yoke 123. The member 141 has a thumb nut 146 which engages with the threaded portion of the member 141 and is held in any desired portion thereof by means of a screw. A spring 147 is fastened to the plate 13 as shown in Fig. 1 and engages with the rod 138 in order to maintain the armature 132 in its "up" position and to maintain the yoke 123 in its "down" position. In other words, the mechanism is maintained in the position as shown in the drawings by means of this spring. The thumb nut 146 limits the movement in one direction and the thumb nut 135 limits the movement in the opposite direction when the armature 132 is attracted.

Referring again to the reciprocating bar 76 and particularly to Figs. 4 and 10 and 11, which show a part 148 which may be integral with the reciprocating bar 76 and which has at its central portion thereof a cam recess 149 in which a pin 150 engages during the normal position of the reciprocating bar 76. This pin is attached to a spring 151 which is adapted to make contact with a companion spring 152 when the shifting bar is reciprocated by means of the electromagnets 82 and 83. These springs are suitably supported by means of the bracket 153 which is suitably fastened to the plate 13. These springs, as shown, are insulated from each other so as to maintain an open circuit when the pin is engaging in the recess as shown in Fig. 11.

Referring now to the circuit arrangement which is used in conjunction with my invention and which is shown particularly in Fig. 12, I show a battery 154 which is connected by means of a conductor 155 through the winding of the electromagnet 82 and by means of the conductor 156 to a key 157 which forms one of a number of keys disposed at the entrance of the establishment. This key is adapted to make connection with the contact 158 which is connected to a conductor 159 that leads back to the negative side of the battery.

The electromagnets 129 and 130 are connected in series with the battery 154 and are connected up to a pair of springs 160 and 161 which are adapted to contact when the eccentric 162 on the clock 163 is rotated. The spring 160 is connected by means of a conductor to the other side of the battery. The arrangement is such that the circuit is closed through the electromagnets 129 and 130 once every minute and thus the type wheels shown in Fig. 4 are advanced at one-minute intervals.

We will now consider a workman Number 1 as entering the establishment in the morning. He will actuate the "In" key 164 so that connection is made with the contact 165, so that the armature 112 is rotated about the pivot 111 by means of the electromagnet 113. This throws the member 109 into position so that the word "In" is directly below the platen 42. The workman will then press the key 157 so that the circuit is closed from the battery 154 through the conductor 155 and through the electromagnet 82, and through the conductor 156, through the spring 157 and contact 158 and conductor 159, back to the negative side of the battery. The energization of the electromagnet 82 draws the armature 81 to the right and since the member 79 is rotated, the shifting bar 76 is forced toward the left. This shifting bar will cause the springs 151 and 152 to make contact inasmuch as the pin 150 is forced downwardly and out of the recess 149. A circuit is then closed from the battery through the conductor 155, through the conductor 166, through the windings of the electromagnets 19 and through the conductor 167, through the springs 151 and 152 through the conductor 167 and through the conductor 159 leading to the negative side of the battery 154. The energization of the electromagnets 19 attracts the armature 24 as shown in Fig. 1, when the platen 42 is brought downward and carries the paper 34 with it against the type wheels and the numeral "1" which is in line with the platen and the word "In" which is also in line with the platen. The ribbon 72 is also carried down by means of the platen against the type which is in line with it. Thus, the notation is made upon the paper and a per-

manent record thereby secured. Since the key 157 is closed against the contact 158 just for an instant, the platen 42 will be brought into its "up" position by means of the 5 spring 64 after the circuit has been opened.

We will now consider the circuit arrangement for workman number 5, who has assigned to him the key numbered 5 as shown in the circuit drawing. As this workman 10 enters the establishment, he also actuates the "In" key so that the word "In" is thrown into position, that is to say, in line with the platen 42, after which he depresses his key 168, thus closing a circuit from the positive 15 side of the battery through the conductor 169, through the winding of the electromagnet 83, through the conductor 170, through the conductor 171, and through one winding of the electromagnet 93, and from there by means of a conductor 172, through 20 the key 168, and through the contact 173 and from there back to the negative side of the battery. This will serve to draw the armature 81 toward the left and consequently the 25 shifting bar 76 will be forced toward the right and the boss 86 on this bar will be brought against the armature 92 associated with the electromagnet 93, this armature having been brought down upon the energization 30 of the magnet, and thus the numeral 5 will be brought into line with the platen. After this shifting movement of the shifting bar 76 and after the numeral 5 has been brought into printing line, the circuit will 35 be closed through the printing magnets 19. The current will take the following course: From the positive side of the battery through the conductors 155 and 166, through the windings of the electromagnets 19, through the conductor 167, through the 40 springs 151, 152, through conductors 167 and 159, and back to the negative side of the battery. When the circuit is closed through springs 151, 152, the platen is brought down 45 so as to print the workman's number on the paper and the time at which he enters the establishment. The paper has been advanced since the first workman entered by means of the pawls 27 engaging the teeth of 50 the ratchets 29 below the position as shown in the drawings, owing to the energization of the electromagnets 19, and when the arms 23 are forced upward by means of the spring 64, the ratchets and the disks 32 are 55 rotated, thus advancing the paper a certain distance.

We will now consider a workman as leaving the establishment at a certain hour. It is to be remembered, of course, that the clock 60 mechanism is rotating constantly and advancing the type wheels 120 and 121 so as to correspond with the time of the day. We will consider that a workman whose number is 6 is leaving the establishment. He will then actuate the key 175 so that connection is

made with the spring 174. Current will then flow from the positive side of the battery through the conductor 155, through the winding of the electromagnet 114, through the contact 175, the spring 174, and through 70 the conductor 159, back to the negative side of the battery. This will actuate the armature into a position as shown in the drawing and consequently throw the lever 107 into a position so that the member 109 is forced toward the left, thus bringing the word "Out" into line with the platen 42. The workman will then depress the key 176 which makes connection with the contact 177 and the following circuit is closed: 80 From the positive side of the battery through the conductor 169, through the windings of the electromagnet 83, through the conductor 178, through the spring 176 and contact 177, and through the conductor 85 159, back to the negative side of the battery.

The shifting bar 76 will be forced toward the right until the pin 101 strikes the post 99, when the numeral 6 is brought into the printing line, after which the circuit is 90 closed through the printing electromagnets 19, through the following path from the positive side of the battery, through the conductors 155, 166, through the windings of the electromagnets 19, through the conductor 167 and springs 151 and 152, conductors 167 and 159, back to the negative side of the battery. The energization of the electromagnets causes the platen to force the paper 34 and the ribbon 72 against the type 100 which are in line with the platen. Thus a notation is made of the number of the workman as well as the month, day, and the time of day, and the year, on which he left the establishment. 105

Since this particular mechanism is designed to be employed as a check upon the watchman employed, a key is assigned to the watchman, which he must actuate at different periods of the night during which 110 he is at work. The key for the watchman is lettered "W" and as he actuates this key, the following circuit is closed: From the positive side of the battery, through conductors 155 and 166, through electromagnets 115 19, through conductors 167 and 179, through the key "W", and contact 180, and from there through conductor 159 back to the negative side of the battery.

It will be noted that the watchman's letter "W" is in line with the platen 42 when the shifting bar is in its normal position, as shown in Figs. 1 and 4. In order to secure the particular time during which he actuates the key assigned to him, the only 125 operation performed by the machine is when the electromagnets 19 are energized so as to force the platen down against the line of type that happens to be in its path.

Each of the keys which are assigned to the 130

workmen may be of such a nature that they may be associated with a suitable locking mechanism, or these keys may be of any other suitable arrangements which may suggest themselves to those skilled in the art.

In the drawing, the workmen's keys, as well as the "In" and "Out" keys, are shown as being disposed at the entrance end of the establishment which may be designated by the dotted lines 181, all of the other mechanism being disposed at a point which is accessible to those who are to retain the records of the different working periods of the workmen.

15 It will be seen that each of the electromagnets 93 and 94 has a winding for active association with the electromagnet 82, another distinct winding for active association with the electromagnet 83. In other words, 20 the arrangement which I propose, provides means for energizing the electromagnet 82, alone, the electromagnet 83, alone, the electromagnets 82 and 93, the electromagnets 82 and 94, the electromagnets 83 and 93, 25 or the electromagnets 83 and 94. Each of these combinations determines a specific position of the type bar, each of these positions being other than the normal position. With the type bar in the normal position an indication may be had, the watchman's indication, as I have pointed out, for instance, and in addition to this indication six others may be had. It will be clear that I could 30 provide an arrangement of greater capacity 35 by providing more "limiting" electromagnets, within reasonable limits, and I do not wish to be considered as limiting myself to any definite number of indications. As before pointed out, when key No. 1 is depressed, the electromagnet 82 is energized alone and the type bar is moved way over to the left to bring the numeral "1" into the printing line.

40 When the key No. 2 is depressed, the electromagnets 94 and 82 are energized. In this condition the armature 87 is brought down to be engaged by the lug 85 and the bar is stopped in position with the numeral "2" in the printing line.

45 When key No. 3 is depressed, the electromagnets 93 and 82 are energized and the armature 92 is brought down to be engaged by the lug 84—and the bar is stopped with the numeral "3" in the printing line.

50 When key No. 4 is depressed, electromagnets 94 and 83 are energized. This brings down the armature 87 to be engaged by the lug 84 and the bar is stopped with the numeral "4" in the printing line.

55 When key No. 5 is depressed, electromagnets 93 and 83 are energized and armature 92 is brought down to be engaged by lug 86—and the bar is stopped with the numeral "5" in the printing line.

60 When key No. 6 is depressed, electromag-

net 83 is energized alone and the bar is brought over to the limit of its movement with the numeral "6" in the printing line.

The circuit of the printing magnets 19 is normally open, and, as has been described, is automatically closed upon any movement of the type bar. As has been pointed out, the normal indication may be had by merely energizing the printing magnets and the watchman's key, therefore, is merely a switch 75 in shunt of the automatically operated springs 151, 152.

What I claim is:

1. In a recording device, the combination of a horizontally movable type bar, guiding means for said type bar, and electrical means for shifting said type bar longitudinally in both directions from a neutral position. 80

2. In a recording device, the combination of a longitudinally movable type bar having a plurality of characters thereon, means for guiding said type bar, electrical means for shifting said type bar to a plurality of positions, electrical means for determining the said positions and means for making an imprint of the character brought in position. 85

3. In a recording device, in combination, a reciprocating horizontal type bar adapted to occupy a plurality of positions, supports for said type bar, electrical means for shifting said type bar, means for determining the positions of said type bar on both sides from a neutral position. 90

4. In a recording device, in combination, a horizontally shifting type bar adapted to occupy a plurality of positions, a plurality of characters on said type bar, guides for said bar, projections on said bar, electromagnets for shifting said type bar both ways from a neutral position, electromagnets for determining certain positions of said type bar, the armatures of said electromagnets being arranged to engage the bosses on said type bar, means for determining the extreme positions of said type bar. 100

5. In a recording device, the combination of a reciprocating horizontal type bar, supports for said type bar, said type bar having a plurality of characters thereon, spring means for maintaining said type bar in neutral printing position, and electrical means for shifting said type bar both ways from said neutral printing position. 110

6. In a recording device, the combination of a reciprocating horizontal type bar adapted to occupy a plurality of positions, printing mechanism associated therewith, said type bar having a plurality of characters thereon, mechanism for maintaining said type bar in a neutral printing position, electromagnets for shifting said bar both ways from said neutral printing position, and electromagnetic means for engaging said type bar to limit the movement thereof. 120

7. In a recording device, in combination,

- an actuating type bar operating in a single plane, a plurality of type characters disposed longitudinally of said type bar and lying in said plane, printing mechanism associated with said type bar, and electromagnetic mechanism for shifting said type bar into position corresponding to any one of said characters.
8. In a recording device, in combination, 10 a horizontal reciprocating type bar, characters disposed on said type bar, means for maintaining said type bar in a neutral position, a platen with which said type bar co-operates, electromagnets for shifting said 15 bar both ways from a neutral printing position, and electromagnets whose armatures are adapted to coöperate with said type bar to determine a plurality of positions thereof.
9. In a recording device, the combination 20 of a reciprocating type bar, supports for said type bar, said type bar having a plurality of characters disposed on the top thereof, spring means for maintaining said bar in a neutral printing position, printing 25 mechanism having a platen disposed directly above the neutral position of said type bar, electromagnets for actuating said printing means, electromagnets for shifting said type bar both ways from the neutral printing 30 position, and electromagnets for limiting the movement of said type bar in either direction.
10. In a recording device, the combination 35 of a reciprocating type bar, supports for said type bar, said type bar having a plurality of characters disposed on the top thereof, spring means for maintaining said bar in a neutral printing position, printing mechanism having a platen disposed directly 40 above the neutral position of said type bar, electromagnets for actuating said printing means, electromagnets for shifting said type bar both ways from the neutral printing 45 position, electromagnets for limiting the movement of said type bar in either direction, and a switch for closing the circuits through said electromagnets.
11. In a recording device, the combination 50 of a reciprocating type bar, supports for said type bar, said type bar having a plurality of characters disposed on the top thereof, spring means for maintaining said bar in a neutral printing position, printing mechanism having a platen disposed directly 55 above the neutral position of said type bar, electromagnets for actuating said printing means, electromagnets for shifting said type bar both ways from the neutral printing 60 position, electromagnets for limiting the movement of said type bar in either direction, a switch for closing the circuits through 65 said electromagnets, and a pair of contacts adapted to close a circuit upon the movement of said type bar so as to cause the actuation of said printing mechanism.
12. In a printing machine, the combination of a movable type bar, electromagnetic means for moving said type bar, electromagnetic means for determining the movement of said type bar and printing means for printing from said type bar after said bar is moved.
13. In combination, a movable type bar, 70 electromagnets controlling the movement thereof, a plurality of keys for controlling said electromagnets to select the movement of said bar, an electromagnetically operated platen, ribbon mechanism, paper advancing mechanism, "In" and "Out" indicating means, and time wheel mechanism.
14. In a printing machine, the combination 75 of a movable type bar, an electromagnet for moving the bar in one direction, an electromagnet for moving the bar in the other direction, and a plurality of electromagnets each having an armature adapted to be engaged by a part of said bar to limit the movement of said bar, each of said last named electromagnets having a winding for active association for each of said first 80 named electromagnets.
15. In a printing machine, a shifting type bar movable in a single plane, selecting electromagnets therefor, printing mechanism operating at right angles to said plane, 85 electromagnets for operating said printing mechanism, and means for closing the circuit of the printing electromagnets upon movement of the type bar.
16. In a printing machine, a shifting type bar, selecting electromagnets therefor, printing electromagnets, means for closing the circuit of the printing electromagnets upon movement of the type bar, and a manual switch in shunt of said circuit closing means.
17. In a printing machine the combination 100 of a movable type bar, electromagnetic means for moving said type bar, electromagnetic devices for limiting the movement of said type bar, an electric circuit and a key 110 for energizing said electromagnetic means, and a printing platen for striking said type bar when the same is in its adjusted position.
18. In a printing machine, the combination 115 of a movable type bar, means for maintaining said type bar in a neutral position, electromagnetic devices for moving said type bar in both directions from said neutral position, devices for limiting the movements of said type bar and a printing platen for striking said type bar.
19. In a printing machine, the combination 120 of a movable type bar, spring means for maintaining said type bar in a neutral position, electromagnetic devices for moving said type bar, and electromagnetic mechanism for determining the movements of said type bar.
20. In a printing mechanism a type bar 125

- having a plurality of printing characters thereupon, electromagnetic means for determining the alinement of said type bar, an electromagnet for moving said type bar, the movement of said type bar being limited to a single plane, an inking ribbon and a printing platen for striking said inking ribbon against the face of said printing characters.
- 10 21. In a printing machine a stationary printing character, a type bar having a plurality of printing characters thereupon, electromagnetic means for moving said type bar, electromagnetic means for determining the alinement of said type bar with said stationary printing character, a printing platen for striking a record sheet against said stationary printing character, and the character of said type bar in alinement with said stationary printing character.
- 15 22. In a recording device, a plurality of electromagnets, a plurality of printing characters controlled by said magnets, a print-

ing platen, electric circuits for said magnets, and a plurality of keys for energizing 25 said electromagnets in predetermined combinations to bring said printing characters selectively in register with said platen.

23. In a recording device, printing means bearing a plurality of characters, a platen, 30 said printing means being movable to bring each of said printing characters selectively in alinement with said platen, a plurality of electromagnets for selectively actuating said printing means, circuits for said electromagnets and keys in said circuits for determining the electromagnets to be energized.

In witness whereof, I hereunto subscribe my name this 30th day of September, A. D. 40 1912.

ALFRED L. SOHM.
